John B. Seifert

UNITED STATES PATENT OFFICE.

IRVING STANLEY, OF NEW YORK, N. Y., ASSIGNEE TO ANGEL INTERNATIONAL CORPORATION, OF NEW YORK, N. Y., A CORPORATION OF MAINE.

PAPER RECEPTACLE OR CONTAINER.

Application filed May 31, 1921. Serial No. 473,950.

To all whom it may concern:

Be it known that I, IRVING STANLEY, a citizen of the United States, and a resident of the borough of Manhattan, in the city, 5 county, and State of New York, have invented certain new and useful Improved Paper Receptacles or Containers, of which the following is a specification.

This invention relates to paper receptacles or containers usually made of truncated cone shape in which the receptacle is formed by shaping a sheet of material, such as paper, to tubular form with the longitudinal edges secured together in overlapped relation, applying a closure to one end of the tube to form an open end receptacle, and subjecting the receptacle so formed to a parafining bath, and it is the primary object of the invention to provide improved 10 means to secure the overlapped edges of the rolled sheet together and secure the closure in the one end of the tube.

Receptacles or containers of this character, as stated, are made of truncated cone shape together with a closure disk applied to the end of greatest diameter. In closing the open end of the receptacle said end is collapsed so that the opposite portions of the container or receptacle will lie contiguous to each other, and in such position are secured together, and it is a further object 20 of the invention to provide improved means for securing the collapsed end of the receptacle in closed condition.

In the drawing accompanying and forming a part of this specification, Figure 1 is a side elevation of my improved container or receptacle, portions being broken away to show the manner of applying the securing strip to the overlapped longitudinal edges, and to show the manner of securing the closure disk in one end of the receptacle.

Figure 2 is a view similar to Figure 1 but showing the open end of the receptacle collapsed and the closure means secured thereto.

Figure 3 is a sectional detail view of the collapsed end of the receptacle to show the manner of applying the closure means thereto.

Figure 4 is a perspective view of a portion of the closure strip; and

Figure 5 is a perspective view in section of a portion of a disk closure.

Similar characters of reference designate

like parts throughout the different views of the drawing.

In the embodiment of the invention shown in the drawing the container or receptacle is formed from a previous cut sheet or blank shaped to form a tube 6 of truncated conical form with the longitudinal edges in overlapped relation, as shown at 7. The overlapped edges are secured together in overlapped relation by applying thereto a gummed strip of material 8, such as paper. After the sheet has been formed to tubular shape a closure is applied to the end of the tube of greatest diameter to constitute the bottom of the receptacle, this closure comprising a disk 9 peripherally flanged as at 10, said flanged disk being inserted into the end of the tube with the flange extending outward with the edge of the flange substantially flushed with the end of the tube when the juxtaposed portions of the disk flange and tube are upset by rolling the same inward, as shown at 11, thereby firmly securing the closure 9 in the tube against movement longitudinally of the tube, when the receptacle is completed. The receptacle in this shape is then subjected to a parafining bath, not only making the material of the container impervious to liquid and moisture but the parafine impregnates the material of the securing strip 8 positively sealing the container at the overlapped edges, and also sealing the connected portions of the closure 9 with the container.

After the receptacle is filled to close the open end 12, (Figure 1) the upper end of the tube is collapsed so that opposite portions of the tube will lie contiguous to each other as shown at 13 in Figure 3. The open end of the tube is secured in this collapsed condition by a strip of metal 14 having prongs 15 stamped therefrom of substantially triangular shape as shown in Figure 4, said prongs being arranged in staggered relation extending longitudinally of the strip. The strip is applied to one side of the collapsed end when the strip prongs are forced through the material of the collapsed end of the receptacle, as shown at 16 in Figure 3, when said ends are upset at the side opposite to which the strip is located. To open the container the tube with the closing strip 14 is torn or cut off, and should only a portion of the contents of the con-

tainer be used and it is desired to again close the container it is only necessary to fold over the top of the collapsed end of the container.

5 Having thus described my invention I claim:

1. As a new article of manufacture, a paper receptacle or container comprising a sheet of material formed to tubular shape 10 with the longitudinal edges in overlapped relation and secured together by an adhesive strip applied to the outer side of the overlapped edges, and a peripherally flanged disk inserted in one end of the tube, and secured therein by rolling the disk flange and end portion of the receptacle together, thereby forming an open end receptacle, the opposite end of the receptacle being adapted 15 to be collapsed to close said end of the receptacle.
2. As a new article of manufacture, a paper receptacle or container comprising a sheet of material formed to frusto-conical shape with the longitudinal edges in overlapped relation and secured in rolled condition 20 by an adhesive strip applied to the outer side of the overlapped edges, a peripherally flanged disk engaging in the end of the tube of larger diameter and secured 25

therein by rolling the material of the disk flange and tube inwardly, and a parafined coating applied to the inside and outside of the receptacle so formed for the purpose specified.

3. As a new article of manufacture, a 35 paper receptacle or container comprising a sheet of material formed to truncated cone shape with the longitudinal edges in overlapped relation and secured in rolled condition by an adhesive strip applied to the 40 outer side of the overlapped edges, a peripherally flanged disk engaging in one end of the tube and secured therein by rolling the material of the disk flange and tube inwardly, and a parafined coating applied to 45 the receptacle so formed, and the open end of the receptacle adapted to be collapsed to close the receptacle and secured in closed condition by a pliable metallic strip arranged with prongs applied to the outer side 50 of the receptacle with the strip prongs forced through the material of the collapsed end of the receptacle and upset at the side opposite to which the strip is applied.

Signed at the city of New York, in the 55 county of New York and State of New York, this 14th day of April, 1921.

IRVING STANLEY.
